CIRCULAR KNITTING MACHINE

Edwin Wildt and Henry Harold Holmes, Leicester, England, assignors to Wildt and Company Limited, Leicester, England, a British company

Application September 15, 1930, Serial No. 482,013, and in Great Britain September 18, 1929

8 Claims. (Cl. 66—50)

This invention consists in improvements in or relating to circular knitting machines of the type intended for knitting hose or half-hose. In other words, the invention is applied to machines in which provision is made, not only for round knitting, but also for knitting by reciprocation as, for example, when heel- and toe-pockets are to be formed.

An object of the present invention is to provide an improved patterning means for such machines, and accordingly the present invention comprises, in or for a circular hose or half-hose knitting machine, the combination with the needle-cylinder of a jacquard selecting device employing a perforated strip, card or equivalent, or a plurality of such devices spaced apart angularly around the needle-cylinder, which devices are associated with, or intended to operate upon, the needles, the needle-jacks, or other stitch-controlling or stitch-forming elements for determining the pattern or nature of knitting to be produced.

In a preferred form of the invention, there is provided an operative driving connection between a main drive for the machine and movable portions of the jacquard device, or devices, which operative connection includes a clutch, or clutches, for throwing the jacquard device, or devices, into or out from operation at will.

Conveniently, each jacquard device comprises a rotatable platen over which a perforated jacquard strip is to be passed, selectors (for example, radially movable elements) controlled by the jacquard-strip and, operating in conjunction with such device or all of them, a selector-actuating cam, or cams, revoluble about the axis of the needle-cylinder, combined with an operative driving connection between the main drive and the said cam, or cams, which operative connection includes a clutch, for instance, the clutch (or one of them) above referred to.

In order that the invention may be more clearly understood, a preferred example will now be described in detail with the aid of the accompanying drawings, in which—

45 Figure 1 is an elevation of the machine looking from the right of Figure 2;

Figure 2 is a plan of the parts illustrated in Figure 1;

Figure 3, on an enlarged scale, is a section of 50 the lower portion of the machine including the needle-cylinder and driving mechanism on the line 3—3 of Figure 2;

Figure 4 is a perspective view of certain parts connected with the patterning head illustrating 55 an attachment for that head;

Figure 5 is a composite view showing a development of the several cam systems employed and their relation one to the other, and

Figure 6 is a diagrammatic view of a modified form of clutch for coupling the main drive with 60 the jacquard cam.

Like reference numerals indicate like parts throughout all the figures of the drawings.

In the specific example illustrated, six jacquard devices are shown arranged in two sets, whereof 65 those of one set are indicated by the reference numeral 10, and those of the other set by the reference numeral 11. In each case, in Figures 1 and 2, the platen rollers are designated by the reference numerals above mentioned, and in connection with two of them perforated jacquard strips 12 are indicated and a few jacquard-selector devices are shown at 13. It will be understood, of course, that there may be a perforated jacquard strip 12 for each platen and there will 75 be as many selectors 13 as may be required for the desired patterning scope, a few only of the latter being indicated to show their relative positions.

The driving spindles 14 of the three platen 80 rollers 10 are interconnected by bevel wheels 15, and the spindles 16 of the platen rollers 11 are similarly interconnected by bevel gearing 17. The two sets of platen rollers are simultaneously driven in the following manner:—A shaft 18 is 85 connected by bevel gearing 19 (Figure 2) to shafts 20 and 21, of which the shaft 20 carries a pinion 22 which in turn engages a pin-wheel (not shown as it lies beneath the pinion 22) constituting part of a Geneva stop mechanism, the rosette 90 wheel 23 of which is fast on the spindle 14 of the platen roller adjacent to the shaft 18. The shaft 21 drives a pin-wheel 24 forming part of another Geneva stop mechanism, of which the rosette wheel is shown at 25 fast on the spindle 95 16 that is also adjacent the shaft 18. The pin-wheel 24 is illustrated as mounted on the shaft 16, whereas the pinion 22 mounted on its shaft 20 is employed to drive the pin-wheel of the rosette wheel 23 for the purpose of making the direction of rotation of the pin-wheels alike, as, of course, shafts 20 and 21 rotate in opposite 100 senses, due to the arrangement of the bevel gearing at 19.

The shaft 18 is driven in the following manner. On the main driving shaft 26 (Figs. 1 through 3) is a pinion 27 which meshes with an intermediate pinion 28 in its turn meshing with a pinion 29 revolving freely on the shaft 18. Associated with the pinion 29 is a movable clutch member 105 30

110

which is splined to the shaft 18 but is free to move longitudinally thereon to engage or disengage clutch teeth 31 from clutch recesses in the pinion 29. Thus, the shaft 18 can be driven positively 5 from the main driving shaft 26 when the clutch 30 is in the position illustrated in Figure 3, whereby both sets of platen rollers are simultaneously driven and the platen rollers can be thrown out of operation by actuation of the clutch member 10 30 to disengage it from the pinion 29.

One set of platen rollers 10 is allocated to the control of the pattern on one half of the fabric and the other set 11 is allocated to the control of the pattern on the other half of the fabric. In 15 the case of the hose machine to which the present invention relates, one half of the fabric will be the front half including the front of the leg and the instep and the top of the foot, and the other half will comprise the back of the leg, 20 heel and foot-bottom.

Conveniently, the operation of the two sets of platen rollers is so timed by the initial setting of the Geneva stop mechanism (23 and 25) relatively to one another that whilst selectors, such as 13, of one set of jacquard devices 10 are (with their platens stationary) being actuated to determine the pattern, rotation of the platens 11 for positioning their selectors will take place, and vice versa.

30 In the example illustrated, the needle-cylinder is intended to be stationary and has a revolving cam box. In the standard 32 on which, as usual, the machine is supported, there is a bearing for the main driving shaft 26, and the axis of this shaft 35 is in a medial plane separating the two sets of jacquard devices, as can be clearly seen from the drawings.

The jacquard devices comprising platen rollers and selectors may be constructed substantially 40 as described and illustrated in prior specifications Nos. 223,619, 272,277, and 313,657. The selectors 13, when selected by the jacquard strip, are moved forwardly towards the needle-cylinder in a position to be engaged and lifted by a cam, or cams, 45 33 that revolve around the axis of the needle-cylinder 34.

The selectors 13, when they are actuated, (lifted in the present example), by a cam such as 33, 50 may serve to operate any known form of patterning mechanism and the invention is not limited to any particular patterning mechanism to be thus controlled or actuated by the jacquard devices. It is known that such jacquard mechanism can be employed for example for the control of reverse plating sinkers, thread feeding devices, and needles, the actuation of the latter being either by direct engagement with the selectors or through the medium of needle jacks. The 55 illustrated example of the invention may be considered as showing a construction in which the selectors 13 are moved upon their selection to a position to engage beneath a needle or needle-jack, whereby when the selectors are raised by a cam such as 33 the needles are raised for patterning or stitch-controlling purposes. The term 60 "patterning" as applied to the jacquard devices is to be understood as including any form of patterning or stitch-control for which jacquard devices can be employed.

70 The cam, or cams, 33 is, or are, only required to be driven at the times when the jacquard devices are actuated for production of a pattern and will in any case be required to cease during the knitting of the heels and toes. In order to 75 render clear the manner in which this drive takes

place, reference is now made to Figure 3, in which it will be seen that within the main driving shaft 26 there is housed a second shaft 35 that has a splined portion on which is mounted the movable part 36 of a main clutch. In the position illustrated in Figure 3, the clutch is shown engaged with a clutch-plate 37 fast on the main shaft 36, and by means of the splined engagement between the member 36 and the shaft 35 the bevel wheel 38 will be continuously driven in one direction. This meshes with a bevel wheel 39 fast on a vertical shaft 40, and splined to the latter is a movable clutch member 41. Freely rotatable on the shaft 40 is a sleeve 42 integral with a pinion 43 meshing with a ring gear 44 on which the cam 33 is carried. The clutch 41 is shown in driving engagement with the sleeve 42 and, consequently, with the parts as shown the cam 33 will be rotated from the main shaft 26. The cam-box 45 is rotated by means of a pinion 46 fast on the shaft 40 and meshing with a ring gear 47 formed on the cam box 45.

In place of a clutch, such as 41, which is to be engaged and disengaged by some external aid such as that described, it may be replaced by a 100 clutch which, so far as its disengagement is concerned, is self-acting. This may be somewhat in the form shown diagrammatically in Figure 6. The clutch teeth on the part 41 and the co-operating recesses on the part 42 are of the shape shown so that the vertical faces of the teeth are engaged when the part 42 is rotated in the direction requisite for round knitting. Thus, assuming that round knitting is in a clockwise direction, the part 42 will drive the part 41. When, however, the machine commences to reciprocate, as when beginning the heel- and toe-pockets, the gear 46 will constantly change its direction of movement.

With the first anti-clockwise direction of the 115 gear 46 the member 41 will also commence to rotate anti-clockwise, and the sloping surfaces of the clutch teeth and recesses in the parts 41 and 42 respectively will come into driving engagement with one another and the teeth on the 120 clutch part 41 will ride up the sloping surfaces of the recesses and the clutch will be disengaged. It will be held in disengagement by a catch 152 over which the clutch held in disengagement will automatically pass so that the parts will be in 125 the chain line position shown on the drawings. In this case only a relatively short lever 52, that is to say that part of it between the pivot 53 and the clutch, is required.

Under these conditions it is not necessary to 130 "time" out this clutch. When reciprocation ceases and round knitting is again to commence, a trip-rod 153 will be operated from one of the control-drums or the like, thereby permitting the clutch part 41 to be engaged with the sleeve 42. 135 The ring 44 then commences to rotate and this is timed to commence when the clutch 30 is thrown in to commence the drive of the shaft 18.

It will be understood that the ring 44 and the gear 43 will not readily run backwardly owing to 140 the shape of the raising cam which prevents it from passing beneath the selector-levers in the reverse direction. It is this fact which causes the sleeve 42 to remain sufficiently still while the teeth on the clutch part 41 ride up the inclined faces of the slots in the sleeve 42 when reverse motion of the parts commences at the beginning of reciprocation.

The means for actuating the clutch 30 comprises a lever 48 pivoted at 49 in a stationary part 150

of the machine, and having a pin 50 entering an annular recess in the surface of the clutch member 30. The pin 50 also projects outwardly from the lever 48 and is spaced from another outwardly-projecting pin 51.

Between the pins 50 and 51 is situated a curved end of another lever 52 pivoted at 53 in a stationary bracket 54. The other end of the lever 52 engages in an annular groove in the clutch member 41. The curvature of the end of the lever 52, which is engaged between the pins 50 and 51, is such that when the lever 48 is moved to the right in Figure 3 to disengage the clutch member 30 from the pinion 29 it will swing the lever 52 in a clockwise direction about its pivot 53, thereby raising the clutch member 41 and disengaging it from the sleeve 42. Thus, as the rotation of the platen rollers is stopped, so also the rotation of the cam 33 will be stopped simultaneously.

The lever 48 is actuated, as shown in Figure 1, from a main patterning device which may be constituted by a pattern-drum 55, or pattern-chain, or other similar means. In the particular example illustrated, a drum is employed, and it is to be understood that cams can be inserted at the required positions in this drum to move a rod 56, the upper end of which is connected to a crank 57 fast on the spindle 49. Thus, the control of the jacquard mechanism is automatically determined from the pattern-drum 55.

There are two main pattern control drums or their equivalent, the other of which is on the same shaft 60, as a wheel 58 over which passes a pattern-chain 59. On the spindle 60 of the wheel 58 is a ratchet-wheel 61 that is engaged by a pawl 62 pivotally mounted on the end of an arm 63 that is mounted to oscillate on the spindle 60. A rod 64 connects the arm 63 with a crank-pin 65 on a wheel 66 that is geared with the pinion 27 on the main driving shaft 26. By this means, as the main shaft rotates, the wheel 58 and its associated drum is given a step-by-step motion and this is imparted also to the drum 55 through an intermediate gear 67. Consequently, the control of the jacquard devices will be automatic.

As is usual in hose machines, the wheel 66 drives a shaft 68, crank wheel 69, and oscillating sector gear 70 fulcrumed on an axis in the lower part of the frame, and which in its turn meshes with a pinion 71 fast on a sleeve 72. On the sleeve 72 is also a clutch plate 73 into engagement with which the main clutch 36 can be moved as an alternative to its engagement with the clutch-plate 37. The change over of position of the clutch member 36 from that illustrated into engagement with the clutch-plate 73 controlled from means such as the drum 55 or chain 59 changes the machine over from rotary knitting to knitting by reciprocation, and it is when this occurs that the pattern-drum 55 will serve to open the clutches 30 and 41 to disconnect the jacquard mechanism from the main drive.

It will be seen from the foregoing description and the drawings that the timing chain, the control drums and the operative connections between the main drive and the various parts to be driven are all located on the rear and front of the machine and very compactly. In fact, the parts are so compactly arranged that almost the whole space surrounding the cylinder is free from any encumbrance so that all the platen rollers can be placed as closely as possible to the needle-cylinder.

The two end platens of the two sets 10 and 11, that is to say, those adjacent to, and on each side of, the driving shaft 18, are so close to the main driving mechanism that the usual endless jacquard strips would foul part of the mechanism were they to hang straight down. Consequently, in order to avoid setting the platens further away from the cylinder, the jacquard strips will be carried over guides 74 specially provided to steer them clear of the driving and control mechanisms. Thus, the compactness of the jacquard mechanism as a whole is not in any way disturbed.

Above the needle-cylinder is mounted a patterning head 75 which carries in it wale-thread feeders and actuating mechanism therefor, but as this is similar in the main to that described in British Patent No. 331,586, no description of it in detail will be necessary herein. The patterning head is supported from an upper triangular frame 76 which is guided for vertical movement in three uprights 77. The head can be raised and lowered by turning a hand-wheel 78 fast on a shaft 79 and meshing by means of gearing 80 with another shaft 81. Shafts 79 and 81 have pinions 82 which mesh with racks formed in the uprights 77. Thus, as the hand-wheel is turned in one direction or the other the frame 76 will be raised or lowered, thereby raising or lowering the patterning head 75. In the prior British Patent No. 331,586 above mentioned, a control rod 80 is described for controlling the patterning operation of the wale-thread feeders. This control rod is indicated in the present drawings at 83, and is actuated from the pattern-chain 59 through a bell-crank 84, connecting rod 85, crank-arm 86, vertical rod 87, crank-arm 88, connecting rod 89, crank mechanism 90, and vertical control rod 91, the lower end of which is actuated by direct contact with the rear pattern-drum. In order to permit the up-and-down movement of the patterning head, the crank-arm 86 is splined to the vertical rod 87.

Figure 5 shows the cam system for the entire machine and on the left are illustrated the several positions of the needles for the several heights to which the butts are raised, as shown by the short black lines in the lower part of the figure.

Each of the needles is associated with a jack 92 and is raised when so determined thereby, selection of these jacks for patterning purposes being effected by means of the jacquard-selectors 13.

Some of the jacks have long butts 93, shown in chain-lines in Figure 5, and others have short butts, and jacks of one kind alternate with jacks of the other kind around the cylinder. The purpose of this arrangement is in order to be able to produce gaps in the needle circle as described in British Patent No. 331,586 for the purpose set forth therein. Having regard to the fact that the purpose of this division is already fully described and in itself forms no part of the present invention, it will only be necessary briefly to refer to the jack cam system for producing this result. The lower line of cams comprises a lifting cam 94 which engages with the butts 93 of all the jacks to bring them to a uniform height after the needles have passed through the stitch-cam system, the cams being intended to rotate in the direction of the arrow shown above the needle-cam system. Following the cam 94 is a second cam 95 which engages only the long butt jacks and lowers those jacks only, and subsequently a cam 96, which engages with the short butt jacks.

raises those jacks and they raise their associated needles above the level of the remaining needles, as is shown clearly in the upper line of needle-butts indicated by 97 immediately above the cam 96. At this position, out-throw- and deflecting-cams 98 and 99 for the wale-thread feeders serve to move the appropriate feeders to wrap their threads round the needles which are relatively raised. After the wale-threads have been wrapped, a lowering cam 100, operable on the needles, pushes down all the needles and jacks that have been previously raised by the cam 96, whereafter another jack-lifting cam 101, operable only on the long butts 93, raises all the long butt jacks and their associated needles to a height corresponding to that to which the other needles have been previously raised by the cam 96. It follows therefore, that alternate needles having been raised by the cam 96 above the intermediate needles, the latter will now be raised by the cam 101 above the alternate needles first raised, and in this position out-throw-and deflecting cams 102 and 103 act upon the wale-thread feeders appropriate to the needles raised by the cam 101. After the needles have been wrapped with their wale-threads in this manner, the jacquard-selecting cam 33 comes into operation to control the nature of the stitching determined by jacquard selection, and, immediately following this, the needles are partially lowered by cam 104 to pass through the usual needle-cam system 105, 106, 107 and 108.

Previously, the jacquard mechanism has been referred to as a patterning mechanism, but it is to be understood that the term "patterning" is employed herein in its broadest sense to mean any desired control of the stitch that is to be formed. In the present instance, the jacquard devices may co-operate with wale-thread feeders, one for each needle, for producing hose in accordance with prior British Patents Nos. 328,026 or 327,987. That is to say, the wale-threads may be of the same colour as the ground-thread and the jacquard selection serves to raise the needles sufficiently high to cause the wale-thread loop to pass below the latch before the needle is drawn down by the stitch-cam, thus throwing the wale-thread loop to the back. Alternatively, the jacquard mechanism may be employed in the manner described in prior British Patent No. 313,657. As a further alternative, if the machine is equipped with more than one feeder, ordinary jacquard knitting could be produced without the use of the wale-thread "head mechanism".

In Figure 5, the chain-line 109 is intended to represent the level of the verge of the cylinder or, if sinkers are used, the ledge thereof.

If it is required to shog the patterning head 75, mechanism similar to that indicated in Figure 4 may be employed. Above the shaft 18 is another shaft 110 carrying the ratchet-wheel 111 and a cam-wheel 112. On the flat face of the latter is a cam or cams 113 which will engage with a cam-follower at the end of an arm 114 carried on a rock shaft 115.

In splined connection with the upper end of the latter, is an arm 116 connected at 117 by a pin-and-slot connection with the end of an arm 118 fast on a spindle 119 which carries the patterning head 75. On the spindle 18 is a crank-arm 120 which is connected by a link 121 with a rocking lever 122 which oscillates about the spindle 110 and carries a pawl 123 to engage the teeth of the ratchet-wheel 111. As the crank 120 is rotated, the arm 122 will be given an

oscillating movement which, by means of the pawl 123, will advance the ratchet-wheel 111 step-by-step. This will cause the cam or cams such as 113, to be brought into engagement with the arm 114 and thereby turn the rock shaft 115 which, by the connections 116 and 118, will also turn the spindle 119 and the patterning head 75 in order to shog the latter about the axis of the needle-cylinder.

When it is desired to maintain the shogging mechanism out of action, a bluffing cam 124, carried by an arm 125 which rocks about the spindle 110, can be brought beneath the pawl 123 to hold it raised above the teeth of the ratchet-wheel 111. The arm 125 is controlled by a rod 126 from one or the other of the pattern devices 55 or 58.

The shogging device, for the sake of clearness, has been omitted from the other figures of the drawings.

It is obvious that with modifications readily understood to those versed in knitting machines, the invention can be applied to machines having revolving needle-cylinders and stationary cams. In such a case, the jacquard devices will revolve around the axis of the machine in company with the needle-cylinder, but owing to the inertia of the parts thus to be revolved, it is preferred to apply the invention to the stationary needle-cylinder type of machine.

It will be understood from the foregoing description of the preferred form of mechanism illustrated in the accompanying drawings, that in its entirety the hose or half-hose machine comprises the combination of jacquard mechanism 110 and wale-thread feeding mechanism by means of which latter vertical stripes or patterns can be produced; or, by means of which knitting can be formed in the manner described in British Patents Nos. 327,958, 327,987 and 328,026.

By dividing the platens virtually into two sets so that while those of one set are operating to position their selectors those of the other set are stationary, the cam 33 is enabled to operate on those selectors of the group of stationary platens, 120 while selection is being carried out on the other group. This affords ample time also for the wrapping of the wale-threads round the needles of the other group before the cam 33 arrives at a position to raise the selectors which have been brought into its path by the platens.

It is within the invention to employ jacquard selection purely for patterning purposes and not necessarily for controlling the movement of the needle to pass a wale-thread that has been wrapped round it below the latch thereof, as described in British Patent No. 328,026.

We claim:

1. In a circular hose or half-hose knitting machine, the combination of a needle-cylinder, 135 means to actuate the machine both for continuous and reciprocating knitting, jacquard patterning devices spaced angularly apart around the needle-cylinder, and, for the jacquard devices, a main driving shaft, driving means coupling said 140 shaft with said devices and control drums all arranged substantially symmetrically with respect to a plane containing the cylinder axis.

2. In or for a circular hose or half-hose knitting machine, the combination of a needle-cylinder, 145 means to actuate the machine for both continuous and reciprocating knitting, jacquard selecting patterning devices spaced angularly apart around the needle-cylinder, means to arrest the operation of said jacquard devices during recip-

- roating knitting and, for the jacquard devices, a main driving shaft, gears coupling said shaft with the jacquard devices and control drums all arranged substantially symmetrically with respect to a plane containing the axis of the cylinder. 5
3. In a circular hose or half-hose knitting machine, the combination of a needle-cylinder, means to actuate the machine both for continuous and reciprocating knitting, jacquard patterning devices spaced angularly apart around the needle-cylinder and each comprising a platen; a jacquard actuating cam, a driving member and clutches for operatively connecting the latter with the platens and with the cam, 10 means to throw into and out of operation together, 80
- 10 4. In a circular hose or half-hose knitting machine, the combination of a needle-cylinder, means to actuate the machine both for continuous and reciprocating knitting, jacquard patterning devices spaced angularly apart around the needle-cylinder and each comprising a platen; a jacquard actuating cam, a driving member, clutches for operatively connecting the latter with the platens and with the cam, and means 15 interconnecting the two clutches whereby they are thrown into and out of operation together. 90
- 15 5. In a circular hose or half-hose knitting machine, the combination of a needle-cylinder, means to actuate the machine both for continuous and reciprocating knitting, jacquard patterning devices spaced angularly apart around the needle-cylinder and each comprising a platen; a jacquard actuating cam, a driving member, clutches for operatively connecting the latter with the platens and with the cam, and a control drum 20 for controlling the operation of the clutches. 95
- 20 6. In a circular hose or half-hose knitting machine, the combination of a needle-cylinder, means to actuate the machine both for continuous and reciprocating knitting, jacquard patterning devices spaced angularly apart around the needle-cylinder and each comprising a platen; a jacquard actuating cam, a driving member, clutches for operatively connecting the latter with the platens and with the cam, and a control drum 25 for controlling the operation of the clutches. 100
- 25 7. In a circular hose or half-hose knitting machine, the combination of a needle-cylinder, a main driving shaft, a continuous gear for driving the machine for continuous knitting, a quadrant gear for driving the machine for reciprocating knitting, a clutch device for alternatively connecting the continuous and quadrant gears to the main driving shaft, jacquard patterning devices spaced angularly around the needle-cylinder, a clutch forming part of an operative connection between the main driving shaft and the jacquard devices, and control means for said clutch so timed that when the clutch for the quadrant gear is moved to couple the latter with the main driving shaft the clutch for the jacquard devices is disconnected. 105
- 30 8. In a circular hose or half-hose knitting machine, the combination of a needle cylinder, means to actuate the machine both for continuous and for reciprocating knitting, jacquard patterning devices spaced apart angularly around the cylinder, said devices each comprising a platen roller, a perforated jacquard element and a plurality of movable selectors in association therewith, a driving member, a selector-actuating member and an interruptable connection between the driving member on the one hand and the 110 platens and selector-actuating member on the other hand. 110
